1 Inventor:

Julius Rebsamen,
By his wife, L. C. Miller,
Attest,

UNITED STATES PATENT OFFICE.

JULIUS REBSAMEN, OF CHICAGO, ILLINOIS.

ART OF REFRIGERATION.

1,425,216.

Specification of Letters Patent. Patented Aug. 8, 1922.

Application filed December 29, 1920. Serial No. 433,763.

To all whom it may concern:

Be it known that I, JULIUS REBSAMEN, a citizen of the United States, residing at Chicago, in the county of Cook and State of Illinois, have invented a new and useful Improvement in the Art of Refrigeration, of which the following is a specification.

The present invention relates to the art of refrigeration and more particularly to refrigeration as applied to the freezing of water for the production of ice.

In the usual refrigeration process for the production of ice, tanks of large size are required as containers for the brine by which the water to be frozen is cooled, the water being contained in relatively small cans for the production of can ice or in large cans of great length for the production of plate ice, these water containers being immersed in the brine tanks. The brine is, in turn, cooled by a refrigerant passed through coils immersed in it. By reason of their large size these brine tanks are expensive in construction and must be of strength sufficient for supporting the great quantity of brine used. Likewise, where water is frozen by refrigerating coils immersed in it, as in ice skating rinks, the tanks utilized for the water must be sufficiently deep for the reception of the cooling coils, thereby necessitating the use and cooling of relatively large quantities of water and the construction of large and deep tanks.

By the present invention it is possible to utilize shallow tanks of water where large sheets are to be frozen or to dispense entirely with the use of brine tanks where ice is to be produced in cans or plates. Furthermore, the low temperature of the atmosphere may be utilized in the present operation to effect or aid in effecting the freezing process. Further advantages of the present invention will be clearly indicated by the description thereof hereinafter given.

In accordance with the present invention the formation of ice is effected by directing against the water container jets or sprays of a cold cooling liquid, such as brine and withdrawing the cooling liquid, which may, if desired, be again cooled and reused. The spraying of the water container with the cooling liquid is continued until the water in the container has been completely frozen and converted into ice of the proper temperature.

In the accompanying drawings I have illustrated an apparatus suitable for practicing my invention. In these drawings

Figures 1 and 2 illustrate respectively the left and right portions of a sectional view of a plant for carrying out the invention, and

Fig. 3 is a transverse sectional view on the line 3—3 of Fig. 1.

Referring more particularly to the drawings, the numeral 10 indicates a building suitable for housing the apparatus for carrying out the process. In this building a relatively large chamber 11 is set off by partitions 12 and 13, preferably of heat insulating material, and is likewise lined with heat insulating material, as at 14, 15 and 16. The bottom of this chamber is drained, preferably by inclining it from the ends to the center, where a transverse trough or drain 17 is provided. The chamber is supported in any suitable manner, for example, on transverse joists 18.

In the upper part of the chamber 11 the cans 19 are supported on spaced channel-iron beams 20. Somewhat below the cans 19 and preferably between the transverse rows of the cans the transverse brine pipes 21 are arranged, these pipes being provided with spray nozzles 22. The arrangement of the brine pipes and spray nozzles is such that the sprays of brine from the nozzles are distributed as uniformly as possible over the sides and bottom of the cans. The sprayed brine is withdrawn from the cans by the action of the force of gravity, falling down over the longitudinally arranged guides 23, which direct the brine into the trough-like distributors 26, each of which is arranged over a vertical refrigerating coil 27, in such manner that the brine is caused to flow over the coils in its descent. These coils, which may be, for example, the expansion coils of an ammonia compression refrigerating system, are supplied and discharged through headers 28 and 29 respectively.

The brine, which has descended in contact with the refrigerating coils, falls to the bottom of the chamber, where it drains into the trough or drain 17, which is protected by a screen cover 30. In this trough is a perforated pipe 31, which is connected to the intake of a pump 32. The discharge of this pump is connected to the header 33, which supplies the spray pipes 21. The

pump and the connections therewith external to the insulated chamber 11 may be thermally insulated in any desired manner.

At the end of the freezing chamber 11

5 and separated from it by partition 12 are two superposed chambers 34 and 35 separated by a horizontal portion 36. These chambers are like chamber 11, completely enclosed by thermal insulating material.

10 An opening 37 is provided between the upper chamber 34 and the upper portion of the chamber 11, and an opening 38 provided with a door 39 is provided in the partition 36 between chambers 34 and 35. Fans 40

15 are located in the chamber 35 which draw the air from within that compartment and discharge it through opening 41 into the lower portion of chamber 11 in which the refrigerating coils are provided. Openings 42 and 43 are provided from chambers 34 and 35 respectively to the exterior of the building in which the apparatus is housed, which openings are provided with removable covers 44 and 45 respectively.

20 The freezing chamber 11 is covered by a stop made up preferably in transverse removable sections 46, each section being located over a transverse row of cans. Removal of a top section affords access to the 25 row of cans below it and permits their removal from the freezing chamber for filling with water or discharge of ice.

In operation under usual external atmospheric conditions the cans are filled with

30 water, and the chamber 11 being covered, cooled brine is forced through spray pipes 21 and nozzles 22 and caused to impinge in a fine spray upon the sides of the cans. Under the action of gravity the brine flows 35 in a film down the sides of the cans, withdrawing heat from the water of the can over its sides and at its bottom. The brine 40 drips from the cans upon the guides 23 and into the distributing troughs 26, which distribute them over the refrigerating coils 27.

45 The brine is cooled by the coils, from which it drips into the bottom of the chamber 11, draining into the trough 17. From here the cooled brine is withdrawn by pump 32 and again forced in a spray against the cans, the spraying resulting in a further cooling of the brine.

To aid in the refrigerating process by maintaining a cold atmosphere about the

50 cans and preventing stagnation of relatively warm air in the top of the freezing chamber, the door 39 is opened and the fans 40 set in operation, thereby causing a circulation of air from the upper or freezing portion of the chamber 11 through chambers 34 and 35 to the lower or refrigerating portion of the chamber 11 and back saturated with moisture to a greater or less extent to the upper portion of the chamber. When 55 the external atmosphere is very cold, for in-

stance, at 15° F. or below, it may be used to aid the action of the refrigerant in coils 27 or even to entirely supplant the use of the refrigerant in the following manner. The door 39 is closed, separating compartments 34 and 35. Doors 44 and 45 are opened, giving access from the compartments 34 and 35 to the exterior atmosphere. The cold air is then drawn into compartment 35 by fan 40 and forced along the coils 70 27, down which brine flows and is cooled by the current of air. The air then circulates around the cans, aiding in cooling them, having been saturated with moisture by its contact with the brine and passes out 75 through opening 37 into compartment 34 and from there into the open air. The circulation of the brine is the same as before.

80 Removal and replacement of the cans is effected by means of a crane 47 which travels 85 on longitudinal rails 48. By this crane cans of ice are withdrawn from the freezing chamber 11 after removal of the corresponding top section 46, taken to the thawing chamber 49 and from there to the tilting 90 platform 50, where the ice is discharged and the cans refilled with water from the tank 51. The cans are then returned by the crane to the freezing chamber.

95 It is readily apparent that the present invention may be utilized for the freezing of plate ice or for the formation of an extended ice surface in a shallow water container, as in skating rinks, or may be otherwise utilized in refrigerating operations.

100 Although the present invention has been described and illustrated in connection with a specific embodiment thereof, it is not intended that the specific details of apparatus or procedure are to be regarded as limitations upon the scope of the invention, except as included in the accompanying claims.

I claim:

1. In refrigerating apparatus, a liquid container, means for spraying a cooling 110 liquid against the container, cooling means below the container, means for collecting the sprayed liquid and distributing it over the cooling means, means for returning it after cooling to the spraying means, and means 115 for passing air over the cooling means and circulating it about the container.

2. In refrigerating apparatus, a chamber, liquid containers supported therein, coils 120 below the containers, means for spraying brine against the containers, means for collecting the sprayed brine and distributing it over the coils, means for passing air over the coils in contact with the brine during passage over the coils, and means for collecting the brine after passage over the coils and returning it to the spraying means.

3. In refrigerating apparatus, a freezing compartment, the bottom thereof being inclined to a drain, liquid containers supported 130

in the upper part of said compartment, means for spraying brine against the containers, coils below the containers, guides between the containers and the coils for collecting the sprayed brine and distributing it over the coils, means for withdrawing the brine from the bottom drain and returning it to the spraying means, and means for forcing external air into the lower part of the compartment over said coils.

4. In refrigerating apparatus, a freezing compartment, containers supported in the upper part thereof, means for spraying brine against the containers, cooling coils in the lower part of the compartment, means for collecting the sprayed brine and distributing it over the coils, means for collecting the brine at the bottom of the compartment and returning it to the spraying means, communicating compartments adjacent the freezing compartment, one of said compartments communicating with the upper portion and the other with the lower portion of the freezing compartment, means for closing communication between said adjacent compartments, means for establishing communication between each of said compartments and the exterior, and a fan in the compartment communicating with the lower portion of the freezing compartment, whereby air may be circulated from the upper to the lower portion of the freezing compartment or external air may be introduced into the lower portion thereof, according to the arrangement of the communications of the adjacent compartments with each other and with the exterior.

5. In refrigerating apparatus, a freezing compartment, containers supported in the upper part thereof, means for spraying brine against the containers, cooling coils in the lower part of the compartment, means for collecting the sprayed brine and distributing it over the coils, means for collecting the brine at the bottom of the compartment and returning it to the spraying means, communicating compartments adjacent the freezing compartment, one of said compartments communicating with the upper portion and the other with the lower portion of the freezing compartment, means for closing communication between said adjacent compartments, means for establishing communication between each of said compartments and the exterior, and a fan in the compartment communicating with the lower portion of the freezing compartment, whereby air may be circulated from the upper to the lower portion of the freezing compartment or external air may be introduced into the lower portion thereof, according to the arrangement of the communications of the adjacent compartments with each other and with the exterior.

JULIUS REBSAMEN.
